UNITED STATES PATENT OFFICE

156,078

DESIGN FOR A TELEVISION ANTENNA

John F. Disch, Chicago, Ill.

Application December 17, 1948, Serial No. 150,220

Term of patent 3½ years

(Cl. D26—14)

To all whom it may concern:

Be it known that I, John F. Disch, a citizen of the United States, residing at Chicago, in the county of Cook, and State of Illinois, have invented a new, original, and ornamental Design for a Television Antenna, of which the following is a specification, reference being had to the accompanying drawing, forming part thereof.

In the drawing, Figure 1 is a plan view of a television antenna, showing my new design.

Figure 2 is a front view of the same with the antenna in a horizontal position.

Figure 3 is a front view of the same with the antenna in a vertical position.

Figure 4 is a side view of the same with the antenna in a horizontal position.

I claim:

The ornamental design for a television antenna, as shown.

JOHN F. DISCH.
